CLAIM

The ornamental design for a feet mat for bathrooms, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a feet mat for bathrooms as it relates to a toilet bottom;

FIG. 2 is a perspective view of the mat showing the design as applied to the perimeter of the bathroom mat; and,

FIG. 3 is a top view of the mat.

The bottom of the mat is flat.

The pattern shown on the top of the mat represents a conventional fabric and is understood to repeat uniformly throughout the mat.

The broken line illustration is for illustrative purposes only and forms no part of the claimed design.
